UNITED STATES PATENT OFFICE.

HENRY W. GRIFFIN, OF NEW YORK, N. Y., ASSIGNOR TO THE UNION
SWITCH AND SIGNAL COMPANY, OF SWISSVALE, PENNSYLVANIA,
A CORPORATION OF PENNSYLVANIA.

CONTROL OF APPARATUS GOVERNING THE PASSAGE OF CARS ALONG RAILWAYS.

No. 798,784.

Specification of Letters Patent.

Patented Sept. 5, 1905.

Application filed April 1, 1905. Serial No. 253,307.

To all whom it may concern:

Be it known that I, HENRY W. GRIFFIN, a citizen of the United States, residing in the borough of Manhattan, city, county, and State 5 of New York, have invented certain new and useful Improvements in the Control of Apparatus Governing the Passage of Cars Along a Railway, of which the following is a specification.

10 My invention relates generally to improvements in the control of automatically-acting train-stops, and more particularly to such automatically-acting train-stops as are used in conjunction with a signal system and which 15 govern the movement of cars by controlling the brake or power systems, or both, of such cars while traveling along a railway.

An object of my invention is to provide means whereby a train which has stopped in 20 obedience to a danger-signal may at once proceed at a very slow speed past the said signal without waiting for the signal to be cleared, and by such movement at a slow speed to cause the automatic stop, which works in conjunction 25 with said signal, to move to its inoperative position, but to make it impossible for a train to proceed past a danger-signal at anything exceeding a very slow speed. Thus on a railway where the system embodied in my invention is employed trains will not be subjected 30 to the prolonged delays which are caused under existing conditions, in which a train having once been stopped in obedience to a danger-signal is obliged to wait until the 35 automatic stop, which works in conjunction with said signal, is moved to its inoperative position by the movement of a preceding train out of the second succeeding block.

The automatically-acting stop to the control 40 of which my invention relates consists, generally speaking, of a trip or lever placed adjacent the railway-track and an electrically-controlled motor adapted to move said trip into such a position that it will not engage 45 with any part of a passing car. This position of the trip I will call its "inoperative" position. When the electrical controlling force is withdrawn from the aforesaid motor, the trip will move under the influence of gravity 50 or a spring or other suitable force into a position which I will call the "operative" position, and when in the said operative posi-

tion it will engage with an arm or lever provided for the purpose and carried by a passing car, and such engagement will cause the 55 brakes of the said car or of the whole train, of which the car forms a part, to be applied, or it will act to cut off the supply of motive power from the said passing car or cars, or in any other suitable manner will cause the train 60 to come to rest.

On a railway system where automatically-acting train-stops are used it is customary to equip one or more cars of a train with one or more depending arms adapted to engage, as 65 above described, with a trip when the said trip is in its operative position and the train or any car of it is passing the trip. As it is the primary function of a train-stop to prevent a train from passing a signal when said sig- 70 nal is in the danger position, and, further, as it is usual to so design and arrange an automatic signal that it will assume the danger position as soon as the first few cars of a train have passed it, it follows that in the case of a 75 long train passing an automatic "clear" signal the said signal would move to the danger position before the whole train had passed it, and if the movement of the trip to its operative position were synchronous with the 80 movement of the signal to the danger position and the trip were placed in proximity to the signal the trip would engage with one of the arms carried by one of the cars of the train, and the train would thereby be stopped. 85

By the arrangement of circuits embodying my invention I provide means for preventing the movement of a trip to its operative position while a train is passing it if the said train is passing it under the authority of a 90 "clear" signal; and, further, I provide means whereby a train which has stopped in obedience to a danger-signal may at once proceed past that signal provided it does so at a low rate of speed or under control, thereby not 95 endangering a preceding train which may be in the block-section governed by said signal, but without causing an undue delay to the train which is passing the signal.

In order to describe the arrangement and 100 operation of the circuits embodying my invention, I will refer to the five diagrammatic views Figures 1, 2, 3, 4, and 5, which accompany this specification. Figs. 1, 2, and 3

show an arrangement of my circuits which is adapted for use on either steam or electric railways and Figs. 4 and 5 show another arrangement which is intended for use on electric railways, in which one or both track-rails are used as a return for the propulsion-current.

In each of the accompanying figures a portion of railway-track is shown which is divided into sections BC CD, &c., in the well-known manner by means of insulations 1 1^a 1^b, &c. Both track-rails or only one track-rail may be so divided. I have shown only one rail divided into sections. In Figs. 4 and 5 provision may be made for using one or both of the track-rails as a return for the propulsion-current used for the motor-cars traveling along the railway. There may be any number of the above-mentioned sections and they may be of any length. I shall call the said sections "block-sections" or simply "blocks." The direction of traffic along the track is from B to D.

The entry of trains to each block-section is governed by a signal 2 2^a 2^b, &c., which may be of any suitable type. The operation of the signals in the present case is automatic and is controlled by the passage of a car or cars along the railway, by means of track-circuits, in a manner well known to the art. Each block-section is provided with a track-circuit, which comprises a battery or other suitable source of current-supply connected to the rails at one end of the block and a relay device connected to the rails at the other end of the block, the said relay being supplied with current from the said source along the track-rails of the block-section. In Figs. 1, 2, and 3 I have shown the source of current-supply for the block-sections in the form of a battery 3 3^a 3^b, &c., supplying direct current, and the relay 4 4^a 4^b, &c., is of a type adapted to respond in the movement of its armature to the presence or absence of current in its coils, the coils being connected to the rails and deriving their current from the battery, as above described. In Figs. 4 and 5 I have shown the source of current-supply in the form of transformers, the primary coils of which are connected to main conductors leading from the power-house or main source of current-supply, and the secondary coils of said transformers are connected to the track-rails of the block-sections to which they respectively belong. I have given these transformers the same designating characters as the track-batteries 3 3^a 3^b, as they perform the same functions, although in the case of the batteries in Figs. 1, 2, and 3 direct current is supplied to the track-relay and in Figs. 4 and 5 alternating current is supplied to the relays 4 4^a 4^b, which are adapted to respond to the presence or absence of the said alternating current in their coils. It is to be understood that the kind of current used in the track-circuits does

not affect the operation of my invention so long as the track-relays respond in the desired manner to the presence or absence of current in their coils, and, further, that I do not limit myself to any specific kind of source for the said current. Each relay is provided with an armature carrying two contact-fingers 5 and 6, 5^a and 6^a, 5^b and 6^b, &c., and when the relay is energized, owing to the presence of current in its coils, the armature is attracted and contact made at the points e and f^a e^a and f^b, &c. When the contacts e e^a e^b, &c., are made, a local circuit is closed in the well-known manner through the operating mechanism of the signal, and the signal is thereby moved to the clear position. This local circuit may be traced as follows: Starting from one pole of generator G the current flows along main conductor P, through wire 7, controlling mechanism of signal, wire 8, contact e, contact-finger 5, through line-wire 9 to contact f^a on relay of succeeding block-section, thence to main return-conductor R, and thence to the other pole of generator G, from whence it started. The generator G may be replaced by a battery or other suitable source of electrical energy or, if preferred, a separate local battery or other source of electrical energy may be used at each station B C D, &c. I do not limit myself to the above or any specific arrangement of local circuits for controlling the movements of the signals.

11 11^a 11^b, &c., designate train-stops which are controlled by the circuits embodying my invention. One of these train-stops is located near the entrance end of each block-section, and the location of any train-stop relatively to the entrance end of its block-section may be determined by the speed at which it is desired that a train shall enter the said section against the indication of a danger-signal.

By the term "depending arm" I mean any arm, lever, or equivalent member that is carried by a car and is adapted to engage with a trip when passing the same, and thereby to apply the brakes or otherwise stop the car or the train of which said car forms a part. Each stop is provided with a trip 12 12^a 12^b, &c., which when in its operative position, as shown at B, Fig. 2, will engage with the depending arm of any passing car, and thereby stop the car, as already explained. When a trip is in its inoperative position, as at B, C, and D, Fig. 1, it will not engage with any depending arm. The movement of any trip 12 to the inoperative position is effected by its motor 11 when the said motor is energized by current flowing through the circuits embodied in my invention, and its movement to the operative position is effected by gravity or a spring or any other suitable force which acts constantly in opposition to the force of the motor. The said movement of the trip to its operative position takes place as soon as and whenever its motor is deenergized. I do not

limit myself to the use of any specific type of train-stop so long as it is capable of being controlled electrically.

Each trip in my invention is controlled as to its inoperative position by two circuits, and when both or either of the said circuits are closed the trip will thereby be moved to and held in its inoperative position; but if both of these circuits should be open at the same time the trip will be moved by gravity or other applied force into its operative position. Consequently in order that a car or cars may pass any trip without being stopped thereby it is necessary that at least one of the two circuits aforesaid should be closed. These two circuits I will call, respectively, the "primary" and the "secondary" circuit. The primary circuit of any stop is normally depended upon to keep said stop energized, and thereby to keep its trip in the inoperative position. The secondary circuit I employ to energize its stop when the trip is in its operative position (owing to the presence of a train in the succeeding block, as I will presently show) and it is desired to allow a second train to pass the said trip at a very low rate of speed. The primary circuit may be traced as follows: starting from one pole of generator G through main conductor P, wire 15, controlling mechanism of stop 11, wires 14, 13, and 9 to contact f' on contact-finger 6^a of track-relay at the succeeding signal, and wire 10^a back to main conductor R, and thence to the other pole of the generator G, from whence it started. It will be seen that this so-called "primary" circuit will hold any trip in its operative position so long as the track-relay 4^a, &c., of the succeeding block-section remains energized—that is to say, so long as the said succeeding block is not occupied by any car or cars.

The secondary circuit in Figs. 1, 2, and 3 may be traced thus: from generator G along P, wire 15, stop 11, wire 14, contact g , contact-finger 6, wire 10, and conductor R back to generator, and in Figs. 4 and 5 the secondary circuit flows as follows: from generator G along P, wire 15, stop 11, wires 14, 13, and 17, contact h when closed, contact-finger 18, wire 16, conductor R to generator. It will be seen that the above-mentioned contact h forms part of or is attached to the armature of a relay 21, being closed when the said relay 21 is energized and opened when the relay is deenergized. This relay has one pole connected by the wire 20 to a short length of rail 19, and its other pole is connected by the wire 22 to the return-rail T of the electric railway. The ordinary contact-shoes which are always carried on both sides of electric motor-cars are made use of in my invention to convey current from the third or power rail S to the short rail 19, and thereby through wires 20 and 22 and the return-rail T to energize the relay

21 under certain conditions, which I will hereinafter more particularly describe.

I will now proceed to describe the manner in which the automatic stops are controlled by means of the circuits and apparatus embodied in my invention, and for this purpose I will first refer to Figs. 1, 2, and 3, which, as above stated, show circuits and apparatus which may be applied to either steam or electric railways.

Referring first to Fig. 1, I there show two complete block-sections BC CD, also the exit end of block AB and the entrance end of block DE. Block CD is clear of trains and the track-relay 4^a is therefore energized by current which flows from the source 3^b through the track-rails and thence through the coils of the relay 4^a, thereby attracting its armature and making contact at e' between contact-finger 5^a and wire 8^a, and also the contact f' between 6^a and wire 9. Block DE is also clear of trains and the relay 4^b is in like manner energized, thereby closing the contacts at e^2 and f^2 . Current now flows from generator G through conductor P, wire 7^a, controlling mechanism of signal 2^a, wire 8^a, contact e' , contact-finger 5^a, line-wire 9^a, contact f^2 , contact-finger 6^b, wire 10^b, and return-conductor R back to generator G. This is the controlling-circuit of signal 2^a, and when the said circuit is closed, as shown, the signal is thereby moved to its clear position. By the closing of contact f^2 another circuit is made which may be traced as follows: from generator G through conductor P, wire 15^a, stop 11^a, wires 14^a 13^a 9^a, contact f^2 , finger 6^b, wire 10^b, conductor R, back to generator G. This is the primary circuit of stop 11^a, and so long as this circuit is closed, as shown, at the point f^2 the stop 11^a will be energized and the trip 12^a thereby held in its inoperative position. It will be seen that, as above stated, the energization of the stop 11^a by its primary circuit depends on the closing of the contact f^2 and that this contact is closed when and as long as the block-section DE is clear of cars. In like manner the stop 11 at B is energized and the trip 12 thereby held in its inoperative position so long as the block CD is free of cars, and the relay 4^a thereby energized and the contact f' consequently held closed. At F, I have shown a car or train of one or more cars which has entered the block BC and is now traversing same. As soon as the train F began to enter the block BC the source 3^b of electric power was short-circuited in the well-known usual manner and the current from said source then began to flow through the low resistance of the wheels and axles of the train instead of through the higher resistance of the relay 4, and the said relay was thereby deenergized and the contacts at e and f thereby opened, as shown. The opening of the contact e breaks the con-

trolling-circuit of the signal 2, and thereby causes it to assume the danger position, as shown. The primary controlling-circuit, however, of the stop 11 is intact, as it is only possible to break this circuit at the contact-point f' , and that contact-point is held closed by the relay 4^a so long as the block CD is clear of cars. Consequently the trip 12 is held in its inoperative position by the stop 11 while the train F is passing it, and the said trip 12 will not move to its operative position until the train F or the first part of said train passes onto the block CD, thereby deenergizing the relay 4^a and opening the primary circuit of stop 11 at the contact-point f' .

Referring now to Fig. 2, I there show the train F as having passed onto block CD, and thereby deenergized relay 4^a and opened the contacts e' and f' . By the opening of contact e' the controlling-circuit of signal 2^a is broken and the signal thereby caused to move to its danger position, as shown. By the opening of contact f' the controlling-circuit of signal 2 is broken and that signal thereby maintained in the danger position which it had assumed when the train F entered block BC. The contact f' , however, besides forming a part of the controlling-circuit of signal 2, also forms part of the primary circuit of stop 11, as already described, and the opening of contact f' , therefore, has the effect of deenergizing the stop 11 and of thereby allowing the trip 12 to assume its operative position. Suppose now a second train H to be following F and that H is now approaching the signal 2. The engineer of train H, seeing the signal 2 in the danger position, should at once stop his train in the rear of signal 2 and refrain from entering block BC until the signal 2 again moves to the clear position. Suppose, however, that for any reason the engineer disregards the danger indication of signal 2 or that he loses proper control of his train and passes the signal 2 at a speed which precludes his stopping the train quickly. Then under those conditions the trip 12, which is now in its operative position, will engage with the first depending arm carried by the leading car of the said train, and by such engagement the brakes will be applied or in some other suitable manner the train will be stopped. As hereinbefore explained, the trip 12 will not move to its inoperative position again until the train passes off the block CD, and thereby allows the relay 4^a to become energized and the contact f' to be closed. It will thus be seen that the trip 12 affords adequate protection to a train F from another train following it too closely. It may be, however, that the traffic conditions upon a railway so equipped with automatic stops are such that too great a delay would be caused by holding the train H on block AB until train F had passed out of block CD, and it may be desired to allow the train H to enter block BC at a low rate of speed or under

control after having stopped a few seconds at signal 2 and to advance with caution to signal 2^a. This desired end I accomplish by means of my secondary circuit, as I will now show.

Referring to Fig. 3, we will suppose that the train H, having stopped at the signal 2, is now proceeding past said signal at a low rate of speed or under control. As soon as the leading wheels of the train enter the block-section BC the relay 4 will be deenergized and the contact-finger 6 will drop, thereby breaking the contact f and closing the contact g . The closing of this contact g completes the secondary circuit through the stop 11, thereby energizing the said stop and moving the trip 12 into its inoperative position, so that it will not engage with any depending arm of the train H. The said secondary circuit may be traced as follows: from generator G, through main conductor P, wire 15, stop 11, wire 14, contact g , contact-finger 6, wire 10, and return-conductor R back to generator G. The stop 11, with its trip 12, is so located that a train entering the block BC at a rate not exceeding a certain predetermined slow speed will deenergize the relay 4, and thereby make the secondary circuit by the closing of contact g , and so move trip 12 to its inoperative position before the foremost depending arm that is carried by the leading car of the train has time to engage the said trip. On the other hand, if the train should enter the block without regard to the signal the trip will engage and stop the train before the secondary circuit has had time to act and move the trip to its inoperative position. The above remarks apply equally to the trips 12^a 12^b, &c.

In Figs 4 and 5 I show an application of the principles embodied in my invention to the case of an electric railway equipped with automatic stops. As in Figs. 1, 2, and 3, two complete block-sections BC and CD are shown with the signals 2 2^a, respectively, controlled by them, and the automatic stops 11 11^a similarly located to and performing the same function as the like automatic stops 11 11^a in Figs. 1, 2, and 3. S designates the third or power rail through which the current flows, which is used for the propulsion of cars traveling along the railway, and 19 19^a 19^b, as hereinbefore stated, is a short length of rail placed adjacent the track-rails and on the side remote from the third rail and is adapted to receive current from the third rail when any car equipped with contact-shoes on both sides is passing the said rail 19, 19^a, or 19^b. To illustrate the operation of the circuits embodied in this part of my invention, suppose a car, or train of cars, to be in the block BC. The relay 4 is thereby deenergized and the signal 2 moved to the danger position through the opening of contact e . The block CD, however, is clear of cars, and consequently the relay 4^a is energized and the contacts e' and f'

are thereby held closed. Current, therefore, flows from generator G, through main conductor P, wire 15, stop 11, wires 14, 13, and 9, contact-finger 6^a, contact f', wire 10^a, wire 16^a, and return-conductor R to generator. The current flowing through this closed circuit energizes the stop 11, and thereby holds the trip 12 in its inoperative position. This is the primary circuit of the stop 11, and it will be seen that it is similar to the primary circuits of Figs. 1, 2, and 3. In order to show the operation of the secondary circuit, I will refer to Fig. 5, in which I have shown the train F as having passed into the section DE, and thereby deenergized the relay 4^b and opened the contacts at e² and f². The opening of the contact f² caused the signal 2^a to remain in the danger position which it assumed when the train F entered the block CD. It also broke the primary circuit of the stop 11^a, thereby causing the trip 12^a to assume its operative position, and when in the said operative position the said trip would act to stop any following train H which might have passed the signal 2^a at a speed greater than the predetermined desired speed. We will suppose, however, that the train H stopped at the signal 2^a and then proceeded at a low rate of speed or under control. Then under such conditions the secondary circuit of stop 11^a would be closed, as follows: As soon as the leading contact-shoe 24 on the first car of the train makes contact with the short rail 19^a current flows from the third rail S through contact-shoes 23 and 24, which are electrically connected, rail 19^a, wire 20^a, relay 21^a, wire 22^a, back to return-rail T of the railway-track, thus energizing the coils of relay 21^a and making contact at h' between 18^a and wire 17^a. The closing of this contact h' establishes the secondary circuit of stop 11^a, and current now flows through this circuit, starting from generator G, through P, wire 15^a, stop 11^a, wires 14^a 13^a 17^a, contact-finger 18^a, wire 16^a, conductor R back to generator G. The closing of this secondary circuit energizes stop 11^a, and thereby holds trip 12^a in its inoperative position, and as long as electrical connection continues to be made between the third rail S and the rail 19 through any pair of contact-shoes of a passing car or cars the above-described secondary circuit will remain closed and the trip 12^a thereby be held clear of engagement with the said passing car or cars. I make the rail 19 of sufficient length to insure any contact-shoe on that side of a car or train of cars making contact with the said rail before the preceding contact-shoe on the same car or train shall have ceased to make contact, so that the relay 21^a is continuously energized so long as any car which carries contact-shoes is passing it, and consequently the train H is enabled to enter the block CD and automatically hold the trip 12^a in the inoperative position, provided that the said train

enters the block at a speed not exceeding that for which the apparatus is arranged. If, however, the train should enter the block at a speed which would preclude its being stopped quickly, the trip will not have time to assume its inoperative position and the train will consequently be stopped. It will of course be understood that there must of necessity be a certain amount of electrical inertia in the coils of relay 21 21^a, &c., and in the coils of the stop 11 11^a, &c., also a certain amount of mechanical inertia in the moving parts of the relay and the trip. Consequently the trip cannot move instantaneously to its inoperative position under the influence of the secondary circuit, and thus it is possible to arrange the relation between the locations of the trip 11^a and the insulation 1^a, on the one hand, and the relative positions of the leading wheels and the leading depending arm of a car, on the other hand, in such a manner as to produce the desired results.

In the foregoing description I have shown the primary and secondary circuits, which control the stops, as being opened and closed by contact-fingers operated by relays. I do not limit myself, however, to this construction, but, if desired, can employ circuit-controllers actuated by some moving part of the signals themselves or of the signal mechanisms to perform the same functions as I have described as being performed by the relay-contacts aforesaid. Furthermore, I do not limit myself to supplying current for the control of the stops from a common source, but, on the contrary, I have no objection to the use of a separate local battery for each signal and the stop adjacent thereto or a separate battery for each signal and each stop, if so desired, though I prefer to use the common source, as shown.

What I claim as my invention is—

1. The combination with a series of block-sections of a railway, of an automatically-acting train-stop comprising a trip for each block-section, and two circuits for each train-stop either of which when closed prevents the trip from being moved to its operative position, one of said circuits being opened by the passage of a train into a block-section succeeding that for which the stop is provided and the other of said circuits being closed by the entry of a train into the block for which the stop is provided.
2. The combination with a series of block-sections of a railway, of an automatically-acting train-stop comprising a trip for each block-section, and two circuits for each train-stop either of which when closed prevents the trip from being moved to its operative position, one of said circuits being opened by the passage of a train into a block-section succeeding that for which the stop is provided and being closed by the passage of the said train out of the said succeeding block-section, the other

of said circuits being closed by the entry of a train into the block-section for which the stop is provided and being opened by the passage of the said train out of the said block-section.

3. The combination with a series of block-sections of a railway, of an automatically-acting train-stop comprising a trip for each block-section, two circuits for each train-stop either 10 of which when closed prevents the trip from being moved to its operative position, one of said circuits being opened by the passage of a train into a block-section succeeding that for which the stop is provided and the other 15 of said circuits being closed by the entry of a train into the block for which the stop is provided, and a source of current-supply for the said circuits.

4. The combination with a series of block-sections of a railway, of an automatically-acting train-stop comprising a trip for each block-section, and two circuits for each train-stop either 20 of which when closed prevents the trip from being moved to its operative position, 25 one of said circuits being opened by the passage of a train into a block-section succeeding that for which the stop is provided and being closed by the passage of the said train out of the said succeeding block-section, the 30 other of said circuits being closed by the entry of a train into the block-section for which the stop is provided and being opened by the passage of the said train out of the said block-section, the aforesaid automatically-acting 35 train-stop being so located relatively to the entrance end of the block-section for which it is provided that a car moving swiftly past the train-stop will be stopped by engagement with the trip before the trip has time to move 40 to its inoperative position, and a car moving slowly past the said train-stop will cause the relay to be energized and the trip thereby to move to its inoperative position before the car has time to engage with said trip.

45 5. The combination with an automatically-acting train-stop comprising a trip and located at a point along an electric railway, of a third or power rail conveying electric energy for the propulsion of cars upon the railway, a 50 section of rail adjacent the railway, conductors carried by the cars and means of conveying current through said conductors from the third rail to the section of rail, a relay device adapted to be energized by said current, two

circuits either of which when closed prevents 55 the trip from being moved to its operative position, one of said circuits being opened by the passage of a train into a block-section succeeding that for which the stop is provided, and the other of said circuits being closed by the 60 energization of the relay aforesaid and opened by the deenergization of the said relay.

6. The combination with an automatically-acting train-stop comprising a trip and located at a point along an electric railway, of a third 65 or power rail conveying electric energy for the propulsion of cars upon the railway, a section of rail adjacent the railway, conductors carried by the cars and means of conveying current through said conductors from the third rail to the section of rail, a relay device adapted to be energized by said current, and a circuit which when closed will move the trip from its operative to its inoperative position, and will hold the trip in the said inoperative 70 position.

7. The combination with an automatically-acting train-stop comprising a trip and located at a point along an electric railway, of a third or power rail conveying electric energy for 80 the propulsion of cars upon the railway, a section of rail adjacent the railway, conductors carried by the cars and means of conveying current through said conductors from the third rail to the section of rail, a relay device 85 adapted to be energized by said current, a circuit closed through the energization of said relay, the said circuit when closed acting to move the trip from its operative to its inoperative position, the aforesaid section of rail 90 being so located relatively to the trip that a car moving swiftly past the automatically-acting train-stop will be stopped by engagement with the trip before the trip has time to move to its inoperative position, and a car 95 moving slowly past the said train-stop will cause the relay to be energized and the trip thereby to move to its inoperative position before the car has time to engage with said trip.

In testimony whereof I have signed my name to this specification in the presence of two subscribed witnesses.

HENRY W. GRIFFIN.
